A. H. WILLETT.
AIR ADMISSION WALL FOR LOCOMOTIVE FIRE BOXES.
APPLICATION FILED FEB. 11, 1916.

1,229,387.

Patented June 12, 1917.

UNITED STATES PATENT OFFICE.

ALFRED H. WILLETT, OF WEST NEW YORK, NEW JERSEY, ASSIGNOR TO AMERICAN ARCH COMPANY, OF NEW YORK, N. Y., A CORPORATION OF DELAWARE.

AIR-ADMISSION WALL FOR LOCOMOTIVE FIRE-BOXES.

1,229,387.

Specification of Letters Patent. Patented June 12, 1917.

Application filed February 11, 1916. Serial No. 77,644.

To all whom it may concern:

Be it known that I, ALFRED H. WILLETT, a citizen of the United States, and a resident of West New York, county of Hudson, and 5 State of New Jersey, have invented certain new and useful Improvements in Air-Admission Walls for Locomotive Fire-Boxes, of which the following is a specification.

My invention relates to improvements in 10 locomotive boiler fire walls and has special reference to improvements in the cross walls of so-called Gaines combustion chamber fire-boxes.

In constructing cross walls of the Gaines 15 type provision is made for the admission of air through the wall and into the firebox space of the firebox. In most instances the air channels extend from the bottom to coping bricks of the wall and communicate with 20 the fire chamber through lateral discharge openings in or beneath the coping bricks. The outer surfaces of the coping bricks are exposed to the intense heat of the firebox gases, which sweep over the wall. In contrast, the undersides of the coping bricks 25 are constantly subjected to the chilling effect of the incoming air which is of relatively low temperature.

I find that these differences in the temperature are the cause of the rapid cracking and breaking down of the coping bricks, and the object of my invention is to overcome the difficulty and make the coping bricks more durable. A further object is to 35 interlock the coping bricks with and upon the wall. I accomplish this object in a very simple way and at slight expense, to wit, by means of deflecting devices or guards by which the rapidly moving streams 40 of relatively cold air in the admission ducts of the wall are prevented from impinging upon the undersides of the bricks which contain air outlet openings. There are several ducts in each wall and hence I provide several deflectors, one for each duct. These deflectors are preferably made of 45 cast metal and they are kept cool by the air flowing in the wall ducts. As hereinbefore explained, the metal deflectors or guards 50 are made to serve as interlocking devices for the coping bricks.

My invention will be readily understood on reference to the drawings which accompany and form part of this specification, and 55 in which I have illustrated my invention in

a preferred form, which, serving as an example, will enable those skilled in the art to adapt the invention to cross walls, air ducts and coping bricks of various designs. In the drawings Figure 1 is a vertical longitudinal section of a locomotive firebox containing my invention;—Fig. 2 is a plural section, one-half thereof being a section on the line X—X of Fig. 1 and the other being a section on the line Y—Y;—Fig. 3 is 60 an enlarged sectional view of the coping brick and interlocking guard shown in Fig. 1; Fig. 4 is a sectional view on the line V—V of Fig. 3;—Fig. 5 is a sectional view on the line W—W of Fig. 3;—Fig. 6 is a 65 straight side view of the interlocking guard or deflector;—and Fig. 7 shows the adaptation of my invention to a Gaines wall and inclined arch.

One of the most difficult positions in which 75 to maintain the coping bricks of a cross wall is depicted in Fig. 1. The cross wall, A, is inclined rearwardly and the tendency of the vibration of the locomotive is to dislodge the coping bricks, B. My invention is admirably adapted for use in such cases, for it 80 serves to interlock or fix the coping bricks upon the top of the wall. In the example shown, the wall contains tubular metal wall stays, C, of now well-known design and 85 function. These stays extend to the top of the wall proper, but terminate short of the bottoms of the coping bricks, B. Each coping brick contains a lateral opening or cavity, B', which opens through the rear side of 90 the wall. Preferably, a complete cavity is not formed in a single coping brick, but is made by the complementary cavities, B', in the abutting ends of two coping bricks, B, as best shown in Fig. 2. The exact form of the 95 cavities, B', is not essential. They may have various forms. But whatever the form of the cavity, I preferably make it to include two vertical recesses, B'', B'', best shown in Fig. 4, and the purpose of which will be explained hereinafter.

According to usual practice the air which rushes up through a tubular stay, C, impinges against the interior or underside of the coping brick, and, as explained, the 105 chilling of the brick soon causes its destruction. I overcome this difficulty by means of the metal deflectors or guards, 2, arranged at the tops of the air ducts and within the cavities of the coping bricks. Each guard has a 110

shank, 3, preferably provided with three lands, 3', and is driven securely into the end of the upright duct or into the upper end of the metal tube, C. The guard or deflector is 5 preferably made of cast iron or cast steel and is a single unitary part. Rising from the tubing shank, 3, is a hood or deflector proper, 4, which preferably overhangs the shank, 3, on all sides. A shoulder, 5, is consequently formed between the shank and the overhanging deflector. This shoulder rests 10 on the top brick of the wall body. An opening, 6, is provided at one side of the casting through which the air which rises through 15 the shank, 3, passes into the discharge opening or cavity, B'. I prefer that the deflector, 4, shall be somewhat smaller than the cavity, B', so that the metal is not in contact with the refractory brick. An insulating material may be used, but I find the air 20 space B' the best for the purpose.

On each side of the part, 4, is a lug or ear, 25 7. These lugs are formed to enter the grooves or recesses, B'', of the coping bricks. Thus the coping bricks are effectively interlocked with one another and also with the body of the wall through the medium of the lugs, 7, and the shank, 3.

It will now be clear that the overhanging 30 deflectors, 4, guard and protect the coping bricks from the air which enters through the ducts, C, and by thus protecting the coping bricks from the chilling effect of the air, the described disruptive temperature differences 35 are avoided.

As indicated in Fig. 7, I may employ the same or similar interlocking guards or deflectors in the top or coping bricks, D, of a

combined Gaines cross-wall and arch. In such cases it is not so necessary that the 40 metal parts shall serve as interlocking devices, but in other respects they are fully as desirable as in the case of the coping bricks of a simple vertical or inclined cross wall. 45

Having thus described my invention, I claim as new and desire to secure by Letters Patent:

1: A firebox cross wall and its refractory coping brick, together containing an air duct 50 and a lateral discharge opening, in combination with a metal deflector smaller than, and arranged in, and spaced from the walls of said opening and guarding said coping brick, substantially as described. 55

2: A firebox cross wall and its refractory coping brick, together containing an air duct and a lateral discharge opening, in combination with a metal deflector arranged in said opening and guarding said coping 60 brick, and said deflector being formed to interlock said coping brick and wall, substantially as described.

3: A firebox wall body containing an air duct, in combination with a coping brick 65 containing a cavity that forms a lateral discharge opening for said duct, a metal deflector positioned in said cavity and smaller than the same but interlocked with said coping brick and said deflector having a tubular 70 shank in said duct, and whereby the coping brick is interlocked with said wall body.

In testimony whereof, I have hereunto set my hand this 1st day of February, 1916.

ALFRED H. WILLETT.
